UNITED STATES PATENT OFFICE.

JOSEPH A. WILLIAMS, OF CLEVELAND, OHIO, ASSIGNOR TO THE WILLIAMS ELECTRIC COMPANY, OF SAME PLACE.

MAGNETO-ELECTRIC GENERATOR.

SPECIFICATION forming part of Letters Patent No. 632,667, dated September 5, 1899.

Application filed June 10, 1898. Renewed July 26, 1899. Serial No. 725,195. (No model.)

To all whom it may concern:

Be it known that I, JOSEPH A. WILLIAMS, of Cleveland, county of Cuyahoga, and State of Ohio, have invented certain new and useful 5 Improvements in Magneto-Electric Generators; and I do hereby declare the following to be a full, clear, and exact description of the invention, such as will enable others skilled in the art to which it pertains to make and use 10 the same.

My invention relates to improvements in magneto-electric generators.

One object of the invention is to increase the efficiency of the U-shaped permanent 15 magnets by a novel and peculiar connection of the pole-pieces to the magnets, so as to form a relative efficient contact and a great effective length of permanent magnet and distribute the magnetism from the magnets uniformly 20 from the central portion of the pole-pieces in opposite directions circumferentially of the armature's sweep.

A further object of the invention is to provide a very simple, convenient, and reliable 25 automatic cut-out, whereby when the generator is not in actual use for ringing the resistance of the armature-winding is automatically cut out of the circuit, so as to avoid weakening of received signals on the bells.

With these objects in view, and to the end 30 of realizing other advantages hereinafter referred to, the invention consists in certain features of construction and combinations of parts, hereinafter described, and pointed out 35 in the claims.

In the accompanying drawings, Figure I is an end elevation of a magneto-electric generator embodying my invention. Fig. II is a front side elevation of the machine, partly broken 40 away and in section to more clearly show the construction. Fig. III is a plan, partly in section and partly broken away. Fig. IV shows the stationary contact and movable contacts of the cut-out and illustrates the manner in which the movable contacts are electrically disengaged from the stationary contact simultaneously with the rotation of the manually-driven shaft.

Referring to the drawings, A A designate 45 the two oppositely-arranged pole pieces or plates that are arranged at opposite sides, respectively, of the circle or sweep of the ar-

mature B. Each pole-piece A has a central arc-shaped portion that extends close to and circumferentially of and partially surrounds 55 the sweep of the armature. Each pole-piece at the lower extremity of its arc-shaped portion extends perpendicularly downwardly, as at a, to the wooden base or support C, and thence is flanged laterally and outwardly, as 60 at a', and overlaps and engages the adjacent end of the inverted U-shaped permanent magnets D, that straddle the pair of pole-pieces. Hence the pole-pieces are arranged between the legs or limbs of the magnets and have 65 flanges a' that engage the extremities of the said magnets and are secured, preferably removably, by means of screws C' to the base or support C.

The generator in the case illustrated comprises three permanent magnets arranged in line edgewise, and the central magnet is snugly 70 interposed between the two outer magnets, so as to avoid any air-space between the adjacent edges of adjacent magnets. The pole-pieces are preferably longer than the aggregate width of the magnets and extend, preferably, beyond the outer edges of the outer magnets.

For the purpose of obtaining a greater effective length of permanent magnet by connecting each pole-piece at the central portion to the connected magnets at a line horizontally bisecting the circular path or sweep of the armature or at the place where the permanent magnets are nearest to the said sweep or path, and for the purpose of distributing 80 the magnetism to the pole-pieces from the magnets uniformly in opposite directions circumferentially of the armature's sweep, I provide a contact-plate G of magnetic material 85 between the outer side of each pole-piece and the inner sides of the adjacent legs or limbs of the magnets, and the said plate G is preferably composed of sheet metal cut and 90 stamped or bent into the shape required to form three perpendicular and flat sections g, engaging the inner sides of the three different magnets, respectively, and an arc-shaped section g' between adjacent straight sections 95 100 and conforming to and fitting the external surface of the central arc-shaped portion of the pole-piece, and the central portion of the arc-shaped members of the contact-plate en-

gage the pole-pieces and magnets at a point horizontally opposite, or approximately horizontally opposite, the axis of the armature, and the curved portions g' of the contact-plate distribute the magnetism from the magnets to the pole-pieces above and below the central place at which the contact-plate engages the magnets.

Each contact-plate G, to prevent its end-wise displacement, has two lugs or flanges g^2 g^3 , that are formed upon opposite ends, respectively, and centrally of the plate and overlapping opposite side edges, respectively, of the engaging pole-piece.

15 Each contact-plate G, for the purpose of preventing edgewise displacement of the permanent magnets, is provided at the top and bottom with two lugs or flanges g^3 g^3 , projecting laterally and outwardly from opposite ends, respectively, of the plate and overlapping and engaging the outer edges of the different outer magnets, respectively.

The armature-shaft b, that operatively bears the armature, is arranged longitudinally of and centrally between the pole-pieces and preferably in the same horizontal plane, as already indicated, with those portions of the contact-plates that engage both the pole-pieces and the magnets, and the said shaft is 25 suitably supported from the end plates K K', that are composed of non-magnetic material and arranged at opposite ends, respectively, of the pole-pieces, and the said end plates are secured, preferably removably, by means of 30 screws K', to the outer sides of the flanges L', formed upon the ends of two horizontally-arranged plates L and L, that are arranged apart vertically a suitable distance and extend from end to end of the pole-pieces, and 35 at the sides have flanges L², that are secured, preferably removably, by means of screws K² to the pole-pieces. The armature has a hub B', that is fixed upon the shaft in any approved manner, and two heads B² B³, arranged at opposite sides, respectively, of the hub, and is recessed between the heads and the hub for accommodating the reception of the wire B³, that is wound upon the armature, and the outer arc-shaped surfaces of the armature-heads are not concentric with the arc-shaped surfaces of the pole-pieces; but the air-gaps between the sweep of the said surfaces of the armature and the pole-pieces shall increase slightly from the central portion of the pole-pieces upwardly and downwardly circumferentially of the said sweep.

40 The armature-shaft at the left-hand end of the machine operatively bears a pinion b', that is in mesh with the driving spur-gear O', that is operatively mounted upon the left-hand end of the manually-driven shaft O, that is arranged horizontally above and parallel with the armature-shaft and supported from upward extensions K³ of the end plates K.

45 The jarring or jerking of the gear when the latter is placed at or near the crank is so great during the operation of the machine

that the bearing of the gear and also the bearing of the pinion are seriously worn, and the wear is evidenced by the objectionable noise 70 that is perceptibly heard during the operation of the worn gearing. By placing the gear as far away from the operating-crank as practicable I have observed that the wear upon the bearings is reduced to a minimum, and, 75 consequently, I place the gearing at the outer side of the left-hand shaft-supporting end plate K.

The automatic cut-out comprises, preferably, a disk or collar P, that is removably secured to the manually-driven shaft by a screw P'. To the disk's side that faces in the direction from which power is applied to the shaft are secured two pawls or contacts P² P², arranged at opposite sides, respectively, of 80 and movable toward the shaft and having one end pivoted to the disk, as at P³, horizontally and longitudinally of the shaft. The said disk is provided with an annular and circumferential rim or flange P⁴, that projects in the 85 said direction, and two springs P⁵ P⁵, that are secured to the internal surface of the said rim, act to retain the different pawls in their normal position, wherein the free ends of the pawls project through slots P⁶, formed in the 90 aforesaid rim, into engagement with a stationary contact Q, that extends around but is arranged a suitable distance from the said rim and is supported in any approved manner—as, for instance, from the pole-pieces, 95 from which it is suitably insulated, as at Q'. Contact Q is electrically connected by the wire Q² with the metallic member b⁴, that by the insulated pin b² is electrically connected with one end of the armature-wire. R and 100 R' designate the two wires leading from and to the machine. Wire R is electrically connected to any metallic part of the machine that is electrically connected with the armature-shaft, and wire R' is electrically connected to member b⁴ and consequently is electrically connected with stationary contact Q. The movable contacts P² are electrically connected with the armature-shaft through the mechanism that lies between them and the 105 said shaft, and consequently the armature-winding is short-circuited when the movable contacts P² are in their normal position and engage the stationary contact Q, and the short circuit of the said winding is removed, 110 so as to throw the latter into the circuit when contacts P² are moved out of engagement with contact Q.

A preferable construction of the cut-out is 115 shown in Fig. IV, where the two pawls are pivoted at diametrically opposite sides, respectively, of and a suitable distance from the shaft O and extend in opposite directions, respectively. Each pawl at its outer longitudinal edge and outer side has a lug or flange 120 P⁷, arranged longitudinally of the pawl and engaged by the spring that acts to retain the said pawl in the latter's normal position. Each pawl at its inner longitudinal edge and outer

side has a long flange P^8 , that extends longitudinally of the pawl. The shaft O is made in two sections assembled endwise. The left-hand section of the shaft carries the gear O' , and the right-hand shaft-section O^3 is tubular and bears the operating-crank O^2 , that at its inner end is provided with an externally-threaded lug O^4 , that engages the correspondingly-internally-threaded outer end of shaft-section O^3 . The right-hand shaft-section O^3 is supported from the right-hand end plate K . The left-hand shaft-section O^3 is supported from the left-hand end plate K and supported at the right-hand end from the left-hand end of shaft-section O^3 by extending into the said left-hand end of section O^3 , that to a limited extent is revoluble upon shaft-section O^3 . Operative connection between the two shaft-sections is made by two flanges or arms $O^5 O^5$, formed upon opposite sides, respectively, of the inner or left-hand end of shaft-section O^3 . One of the members O^5 overlaps the outer side of the flange P^8 of one of the pawls and the other member O^5 overlaps the outer side of the flange P^8 of the other pawl, and the arrangement of parts is such, therefore, that the turn of the shaft-section O^3 in the one or the other direction will cause its arms or flanges O^5 to actuate the pawls to ward each other against the action of the pawl-engaging springs and out of engagement with contact Q and turn the left-hand shaft-section by virtue of the operative connection thus established between the two shaft-sections by members O^5 and pawls P^8 . The gear-bearing shaft-section is prevented from outward endwise displacement by a collar O^6 , fixed upon the said shaft-section at the right-hand end of the shaft-supporting box formed upon the left-hand end plate K , and the crank-bearing shaft-section is prevented from outward endwise displacement by a collar O^7 , fixed upon the last-mentioned shaft-section at the left-hand end of the shaft-supporting box formed upon the right-hand end plate K .

The arrangement of the stationary contact Q and the movable contacts $P^2 P^2$ is of course such that at all times at least one of the said movable contacts in the latter's normal position engages the stationary contact.

Two suitably-arranged bolts $S S$ and nuts S' , mounted upon the shanks of the bolts, and plates or washers S^2 , interposed between the bolt-heads and the magnets and between the nuts and the magnets are employed in drawing the limbs of the magnets together and against the pole-pieces. The two bolts extend through the different outer magnets, respectively, next to the central magnet. The bolt-holes d in the magnets are formed by recesses made in the said edges of the magnets, as shown in dotted lines, Fig. II, and the washers or plates S^2 extend across and act upon the central magnet.

What I claim is—

1. In a magneto-electric generator, the com-

bination with the magnets and the pole-pieces; of contact-plates between the pole-pieces and the magnets, which plates have sections engaging the magnets and having other sections engaging the pole-pieces, substantially as set forth. 70

2. In a magneto-electric generator, a contact-plate snugly interposed between the outer side of each pole-piece and the adjacent portions of the permanent magnets, and consisting of a sheet or plate of magnetic material, and cut or stamped or bent into the shape required to form straight sections engaging the magnets and curved sections conforming to and engaging the outer sides of the pole-pieces, substantially as set forth. 75

3. In a magneto-electric generator, the combination with the two pole-pieces having arc-shaped or curved portions arranged at opposite sides, respectively, of and extending partially around the armature's sweep, and the magnets straddling the pair of pole-pieces; of a contact-plate snugly interposed between the said central portion of each pole-piece and the magnets, and having straight sections engaging the magnets and arc-shaped or curved sections formed between the straight sections and engaging the pole-pieces, substantially as 95 set forth. 85

4. In a magneto-electric generator, the combination with the two arc-shaped or curved pole-pieces arranged at opposite sides, respectively, of the armature's sweep, and the magnets straddling the pair of pole-pieces; of a contact-plate interposed between the outer side of each pole-piece and the magnets, and having sections engaging and conforming to the inner surfaces of the magnets above and below the central part of the arc-shaped or curved portions of the pole-piece and having other sections partially embracing and engaging the outer sides of the pole-pieces above and below the said central part of the pole-piece, substantially as set forth. 105 110

5. In a magneto-electric generator, a contact-plate for interposition between the outer side of a pole-piece and the adjacent portions of the permanent magnets and consisting of a plate composed of magnetic metal or material and cut and stamped or bent into the shape required to form sections partially embracing the pole-piece above and below the central portion of the armature-surrounding portion of the pole-piece, and other sections conforming to and engaging the magnets above and below the said central portion of the pole-piece, substantially as set forth. 115 120

6. In a magneto-electric generator, a contact-plate interposed between the outer side of a pole-piece and the adjacent portion of the permanent magnets, and having two lugs or flanges overlapping and engaging the opposite side edges, respectively, of the pole-piece, substantially as and for the purpose set forth. 125

7. In a magneto-electric generator, a contact-plate interposed between a pole-piece and

the magnets, and having lugs or flanges suitably arranged to prevent edgewise displacement of the magnets, substantially as set forth.

- 5 8. In a magneto-electric generator, a contact-plate interposed between a pole-piece and the magnets, and consisting of a plate of magnetic metal cut and stamped or bent into the shape required to form, first, members 10 engaging the magnets' inner sides, secondly, members engaging the outer side of the pole-piece, thirdly, lugs or flanges overlapping and engaging the side edges of the pole-piece, and, fourthly, lugs or flanges arranged to prevent 15 edgewise displacements of the magnets, substantially as set forth.

9. In a magneto-electric generator, the combination of the supporting-base C; two pole-pieces A A; the permanent magnets D, and 20 the contact-plates G having the magnet-engaging members g and the pole-piece-engaging members g' all arranged and operating, substantially as and for the purpose set forth.

10. In a magneto-electric generator, the combination of the two pole-pieces and the magnets straddling the pair of pole-pieces and arranged in line and contact edgewise, and having the bolt-holes, for the reception of the bolts, that are instrumental in drawing 30 together the magnets, formed by slots or recesses made in edges of the magnets, and the bolts and connected members for drawing the magnets against the pole-pieces, substantially as set forth.

35 11. In a magneto-electric generator, the combination with the pole-pieces and the three permanent magnets arranged in line edgewise with the central magnet snugly interposed between the two outer magnets; of 40 the bolts S, the nuts S' and the plates or washers S², all arranged and operating substantially as and for the purpose set forth.

12. In a magneto-electric generator, the combination of the manually-driven shaft 45 having an external disk, collar or laterally-projecting member; a contact pivoted to the said laterally-projecting member longitudinally of the shaft; a stationary contact arranged to be engaged, by the pivoted contact, when the latter is in its normal position; means acting to retain the pivoted contact in the latter's normal position; and such an operative connection between the pivoted contact and the shaft as will tilt or swing the pivoted contact 50 away, and retain it separated, from the stationary contact during the rotation of the shaft, substantially as set forth.

13. In a magneto-electric generator, the combination with the stationary contact, and 60 a movable contact, of the machine's cut-out; of the manually-driven shaft, and such an operative connection between the latter and the movable contact as will separate the movable contact, and retain the latter separated, 65 from the stationary contact during the rotation of the shaft in either direction, substantially as set forth.

14. In a magneto-electric generator, the combination of the manually-driven shaft; the cut-out's two movable contacts arranged 70 at opposite sides, respectively, of and supported from the shaft; the cut-out's stationary contact partially embracing the annular path along which the movable contacts revolve during the rotation of the shaft, and arranged to be engaged at all times by at least one of the movable contacts in the latter's normal position; means acting to retain the movable contacts in their normal position, and such an operative connection between the movable contacts and the shaft as will cause the movable contacts to be disengaged from the stationary contact upon the rotation of the shaft, substantially as set forth.

15. In a magneto-electric generator, the combination of the manually-driven shaft composed of two sections assembled endwise; a disk or collar operatively mounted or formed upon one of the shaft-sections; a crank operatively connected with the other shaft-sections; two movable contacts carried by the said disk or collar at opposite sides, respectively, of the shaft and movable toward each other; a stationary contact partially embracing the annular path along which the movable contacts revolve during the rotation of the shaft, and arranged to be engaged at all times by at least one of the movable contacts in the latter's normal position; means acting to retain the movable contacts in their normal position, and such an operative connection between the crank-bearing shaft-section and the movable contacts as will cause the movable contacts, during the rotation of the last-mentioned shaft-section, to be disengaged from the stationary contact and transmit motion to the shaft-section that carries the movable contacts, substantially as set forth.

16. In a magneto-electric generator, the combination of the manually-driven shaft 110 composed of two sections assembled endwise; a disk or collar operatively mounted or formed upon one of the shaft-sections; a crank operatively connected with the other shaft-section; two movable contacts carried by the 115 said disk or collar and pivoted, at one end, at opposite sides, respectively, of the shaft, and extending in opposite directions, respectively; a stationary contact partially embracing the annular path along which the movable contacts revolve during the rotation of the shaft and arranged to be engaged at all times by at least one of the movable contacts in the latter's normal position; means acting to retain the movable contacts in their normal positions, and such an operative connection between the crank-bearing section of the shaft and the movable contacts as will cause the movable contacts, during the rotation of the last-mentioned shaft-section, to be disengaged from the stationary contact and transmit motion to the shaft-section that carries the movable contacts, substantially as set forth.

17. In a magneto-electric generator, the combination of the manually-driven shaft composed of two sections assembled endwise; a disk or collar operatively mounted or formed upon one of the shaft-sections; a crank operatively connected with the other shaft-section; two movable contacts supported from the disk or collar and arranged at opposite sides, respectively, of and movable toward the shaft, and each of the said movable contacts having a flange arranged longitudinally thereof; means acting to retain the said contacts in their normal position; a stationary contact partially embracing the annular path along which the movable contacts revolve during the rotation of the shaft, and arranged to be engaged at all times by one of the movable contacts in the latter's normal position, and two arms or flanges formed upon or rigid with the crank-bearing shaft-section and overlapping the one the outer side of the flange of one of the movable contacts, and the other the outer side of the flange of the other movable contact, substantially as set forth. 50
18. In a magneto-electric generator, the combination of the manually-driven shaft composed of two sections assembled endwise, and one of the said sections being hollow and embracing the other section; a crank operatively connected with the hollow shaft-section; two movable contacts supported from the other shaft-section and arranged at opposite sides, respectively, of and movable toward the shaft, and each of the said movable contacts having a flange arranged longitudinally thereof; means acting to retain the said contacts in their normal position; a stationary contact partially embracing the annular path along which the movable contacts revolve during the rotation of the shaft and arranged to be engaged at all times by one of the movable contacts in the latter's normal position; an arm or flange formed on the crank-bearing shaft-section and overlapping the outer side of the flange of one of the movable contacts, 45 and another arm or flange formed upon the said shaft-section and overlapping the outer side of the flange of the other movable contact, substantially as and for the purpose set forth. 55
19. In a magneto-electric generator, the combination of the manually-driven shaft; two movable contacts supported from and arranged at opposite sides, respectively, of and movable toward the shaft, and each of the said movable contacts having a flange arranged longitudinally thereof; means acting to retain the said contacts in their normal position; a stationary contact partially embracing the annular path along which the movable contacts revolve during the rotation of the shaft and arranged to be engaged at all times by one of the movable contacts in the latter's normal position; the operating-crank; a member overlapping the outer side of the flange of one of the movable contacts and a member overlapping the outer side of the flange of the other movable contact, and both of the said flange-overlapping members being revoluble and operatively connected with the crank, substantially as set forth. 60
20. In a magneto-electric generator, the combination of the shaft O comprising a crank-bearing section O³ revolvably embracing the gear-bearing section O⁴; the disk or collar P having the circumferential rim or flange P⁴ slotted, as at P⁶; the pivoted movable contacts P² having the flanges P⁷ and P⁸; the springs P⁵ and the arms or flanges O⁶ upon the crank-bearing shaft-section, all arranged and operating for the purpose shown and specified. 65
